UNITED STATES PATENT OFFICE.

HERBERT S. DE SOLLA, OF DECATUR, ILLINOIS.

COLLAR-BUTTON.

SPECIFICATION forming part of Letters Patent No. 358,433, dated March 1, 1887.

Application filed July 30, 1886. Serial No. 209,550. (No model.)

To all whom it may concern:

Be it known that I, HERBERT S. DE SOLLA, of Decatur, in the county of Macon and State of Illinois, have invented certain Improvements in Collar-Buttons, of which the following is a specification.

The aim of my invention is to provide a simple device which will answer the several purposes of connecting the two ends of the collar-band, attaching the collar thereto, and retaining the scarf or necktie in position.

To this end it consists in a button-like head having a shank curved in a peculiar manner into a hook form, as hereinafter described.

15 In the accompanying drawings, Figure 1 represents a perspective view of my device. Fig. 2 is a vertical section showing the same in its operative position.

Referring to the drawings, A represents a circular head or button having at its upper edge a shank or hook formed integral therewith. This shank extends rearward horizontally from the upper edge of the head, as shown at b, thence upward in a vertical direction, as seen at b', and finally downward at the front in the form of a hook, as shown at b''.

It will be observed that the portion b' stands in a vertical or substantially vertical plane and that the hook-arm b'' is turned forward 30 and downward, so that it stands in advance of the head. It is to be further noted that the upper edge of the button is to be incised adjacent to the shank and the corners turned

forward, as shown at c, thus allowing the device to be inserted the more readily through 35 the collar and shirt-band B.

In making use of the device the head or button is seated against the rear face of the shirt-band. The shank passes inward through the openings in the two ends of the band and thence outward and downward over the upper edge of the band, as shown. The collar C is slipped upward over the shank or hook, and the cravat or scarf D inserted beneath the shank on the outside, as shown.

40 I am aware that various devices for fastening collars and retaining scarfs are already known; but it is to be noted as a distinctive feature of my device that the shank or hook is returned past the face of the button and the 45 latter provided with the lips or shoulders C.

Having thus described my invention, what I claim is—

A collar-button having the head A and the shank extending from its upper edge, said shank being extended forward, as at b, thence 50 upward, as at b', and finally downward past the face of the head, as at b''.

In testimony whereof I hereunto set my hand, this 5th day of July, 1886, in the presence of two attesting witnesses.

HERBERT S. DE SOLLA.
